S. HILL ET AL

FURNACE

Filed Feb. 3, 1926

UNITED STATES PATENT OFFICE.

SAMUEL HILL AND JUHA LATVALA, OF TWEQUA, MICHIGAN.

FURNACE.

Application filed February 3, 1926. Serial No. 85,704.

This invention relates to improvements in furnaces for heating homes, apartments, stores and the like and its object is to provide a neat appearing heating plant that is very 5 economical in the use of fuel and very efficient in the production and distribution or circulation of heat.

With the foregoing and other objects in view the invention consists in the combination 10 and arrangement of parts to be herein-after fully described, pointed out in the appended claim and illustrated in the accompanying drawing which forms a part of this application and in which—

15 Fig. 1 is a view of the furnace in front elevation.

Fig. 2 is an enlarged fragmentary sectional view illustrating the interior construction and arrangement.

20 Fig. 3 is a cross section taken on line 3—3 of Fig. 2.

Like reference characters denote corresponding parts throughout the several views.

The furnace comprises a fire box upon 25 which is disposed the superheating compartment, the fire box and superheating compartment being lined with fire brick and separated one from the other by a grate upon which a plurality of large stones of irregular shapes 30 and sizes are arranged and piled up to almost completely fill the compartment, the fire, smoke and gases from the combustion taking place in the fire box passing up between, around and among the stones which absorb 35 the heat and, after the fire in the fire box has died down or cooled appreciably or after fresh fuel has been added or the fire banked, the stones so arranged will continue to give off a great deal of heat. This type of furnace 40 will be found very efficient and economical where thermostatic control is resorted to as

intermittent periods of intense combustion in the fire box will result in continuous heat of a high degree being disseminated through the building.

The reference numeral 1 denotes the base provided with the feet 2, said base supporting the ash chamber 3 provided with the door 4. The fuel grate 5 separates the ash chamber from the fire box 6 which is lined with fire brick 7, all corners in the several compartments being reinforced by the angle pieces 8 and ornamental reinforcing rings 9 connecting the compartments one to the other to afford a substantial and durable construction. A steel sheathing 10 is provided for each compartment.

The superheating compartment 11 is arranged upon the fire box and separated therefrom by the grate 12 upon which, and upon each other the stones 13 are arranged that practically fill said compartment. The usual smoke pipe 14 is provided in the top 15 and the fire box is provided with the door 16 having the draft regulator 17. The stones 13 absorb the heat given off by combustion in the fire box and radiate the same after intense combustion has ceased and retard the gases escaping therefrom permitting a more thorough combustion of the fuel.

70 What is claimed is:—

A furnace section comprising a grate, walls supported upon the marginal portion thereof, and a lining for the walls supported upon the grate and disposed around the bars of the 75 grate.

In testimony that we claim the foregoing as our own we have hereto affixed our signatures.

SAMUEL HILL.
JUHA LATVALA.
